FLOYD N. BARBER, OF CRAFTON, PENNSYLVANIA, ASSIGNOR, BY MESNE ASSIGNMENTS,
TO THE ELECTRIC CONTROLLER & MANUFACTURING COMPANY, A CORPORATION
OF OHIO.

ELECTRIC SWITCH.

1,227,568.

Specification of Letters Patent. Patented May 29, 1917.

Application filed April 21, 1913. Serial No. 762,642.

To all whom it may concern:

Be it known that I, FLOYD N. BARBER, a citizen of the United States, residing at Crafton, in the county of Allegheny and State of Pennsylvania, have invented new and useful Improvements in Electric Switches, of which the following is a specification.

My invention relates to electro-magnetic devices, and more particularly to electro-magnetic switches of the type in which the switch member is prevented from moving to circuit-closing position as long as the current through the energizing winding is above a certain value and moves to said position as soon as the said current is reduced to the said value.

Referring to the accompanying drawing the figure shows one form of my switch in side elevation, a motor circuit being shown diagrammatically.

On the drawing, N represents a base or support, preferably of slate or other insulating material. On this base, I mount the frame A which supports the winding B, surrounding the vertical core with the poles a and a'.

On the pivot K I pivot the armature, switch arm, or movable member C, having one end within the field of the magnet and 30 magnetically controlled by the pole a. The other end of the member C is bent downwardly and terminates in the contact E insulated from the remainder of the member C. The pivot K is between the ends 35 of the member C. An adjustable stop, for example, the screw H, engages the underside of the member C at the right of the pivot K to limit the right hand movement of the said member and to adjust the air-gap between the top of the magnet and the 40 left-hand end of the said member. The adjustable spring G is attached to the member C to cause or assist the member C to return to the position shown after it has 45 been rotated to the left by the magnetic pull across the gaps between the member C on one side and the magnet frame and the pole a on the other side. The screw J in the member C regulates the air-gap existing between the pole a and the member C, when the latter is attracted to the former.

The armature, switch arm, or movable member D oscillates on the pivot L and has its other end within the influence of the pole or when energized. The member D carries

between its ends the contact F insulated therefrom and adapted to engage with the contact E when the latter is in the position shown and when the member D is attracted to the pole a'.

When the switch S is closed, current flows from the positive side of the line through the switch S, the winding B, the resistance R and the motor M to the negative. The armature or movable member D will at 60 once be drawn up by the magnet and preferably close the magnetic circuit between the pole a' and the lower end of the frame A. The armature or movable member C may or may not be actuated at the same 65 time. The pivot K is so located, the tension of the spring G is so regulated, and the air-gaps between the member C and the frame A and the pole a and between the member D and the frame A and the pole a', 70 are so adjusted by the stop H, that the member C will not be moved provided the current which would flow through the contacts E and F, if closed, would not be excessive for the motor M or other translating device. If the current in the winding 75 is so high that the motor M or its equivalent might be injured in case the resistance R should be short-circuited by the closing of the contacts E and F, the member C will 80 be actuated at the same time as the member D, whereby the contacts E and F will be kept separated. As the current dies 85 down by reason of the increasing speed of the motor M, the current through the winding diminishes and when the current diminishes to such a value that the magnetic pull across the gaps between the member C and the magnet is overcome by the spring G or other bias, as gravity, or both, the member C will oscillate to the right and the contact E will engage with the contact F, thereby short-circuiting the resistance R and causing an increased current to flow 90 through the motor. The member C can be 95 caused to be released at the desired value of current by adjustment of the screw J, or the tension of the spring G.

I do not restrict my invention to the details and combinations shown or described 100 as many changes may be made within the scope of the appended claims.

I claim—

1. In a magnetically-operated device, a winding, a pair of magnetizable arms adapt- 110

ed to be moved by said winding with unequal facility, a contact on each arm, normally separated from each other, the said arms having portions attracted by the winding to maintain the said contacts separated when both arms are moved by the winding and to cause said contacts to engage each other when only one arm is moved by the winding.

10 2. In a magnetically-operated device, a winding, a pair of magnetizable arms adapted to be moved by said winding with unequal facility, a contact on each arm, normally separated from each other, the said arms having portions attracted by the winding to maintain said contacts separated when both arms are moved by the winding and to cause said contacts to engage each other when the current in the winding is 20 reduced.

3. In a magnetically-operated device, a winding, a pair of magnetizable arms adapted to be moved by the winding with unequal facility, a contact carried by each arm, the contacts being separated before the winding is energized, and the said arms having portions attracted by the winding to maintain the contacts separated when both arms are moved by the winding, and to

cause the contacts to be engaged when only one of the arms is moved by the winding, and to cause the winding to move both arms when the current in the winding is above a certain value and to release one arm when the current reaches the said value. 30

4. In a magnetically-operated device, a winding, a pair of magnetizable arms adapted to be moved by the winding with unequal facility, a contact carried by each arm, the contacts being separated before the winding is energized, and the said arms having portions attracted by the winding to maintain the contacts separated when both arms are moved by the winding, and to cause the contacts to be engaged when only one of the arms is moved by the winding, and to cause the winding to move both arms when the current in the winding is above a certain value and to cause one of the arms to move its contact into engagement with the contact on the other arm when the said current is reduced to the said value. 40

45 Signed at Pittsburgh, Pa., this 18th day of April, A. D. 1913.

FLOYD N. BARBER.
